TUBE CLEANING MACHINE

Albert Carter, Cleveland Heights, Ohio, assignor
to Carter Pneumatic Tool Company, Cleve-
land, Ohio, a corporation of Ohio.

Application December 3, 1934, Serial No. 755,727

20 Claims. (Cl. 51—8)

This invention relates to a method of and apparatus for cleaning the interior of tubes, and is especially concerned with a method and apparatus for removing scale from the tubes of a steam boiler or the like. Heretofore, it has been the general practice to remove scale from boiler tubes by using mechanism carrying brushing or cutting tools to brush or cut the scale from the inner surfaces of the tubes. While such methods 5 of cleaning tubes have been more or less successful, the brushing or cutting tools, used in carrying out these methods, have required replacement at frequent intervals. Indeed, several replacements have been required during the 10 cleaning of the tubes of one comparatively small boiler. The operation of such mechanism is therefore expensive, due to the cost of the tools, and also because of the time lost in making the replacement. The latter is often a serious dis- 15 advantage in itself, as, in many instances, the cleaning of the tubes must be accomplished while the boiler is out of operation and hence the time required for changing or replacing the tools lengthens the idle period of the boiler.

Moreover, when cutting tools are used, there 20 is danger, in case the scale is abnormally hard on one side of the tube, for the tool to assume an eccentric position in the other direction and cut away some of the metal of the tube on the opposite side, materially weakening the wall thereof.

The general object of the present invention is 25 to provide a method and apparatus for removing scale and other foreign matter from the inner walls of boiler tubes and the like, in an economical, efficient manner, with rapidity and without 30 danger of injuring the tube.

I accomplish the object above mentioned, broadly speaking, by employing a blast of abrasive material which is directed against the interior 35 of the tube. It is one of the objects of the present invention to provide an apparatus for efficiently handling such blast for progressively cleaning the tube wall.

A further object of the invention is the provision of a mechanism which may be inserted within a boiler tube and provided with a nozzle or blast passage adapted to be wobbled or oscillated by mechanism carried within the tool.

Another object is the provision of a tube cleaning machine, which may be inserted in a tube to be cleaned and which mechanism will remove scale, and the like, from the inner walls of the tube by directing a blast of abrasive material at the walls through a nozzle, which is wobbled, by a 50 portion of the blast stream through mechanism

carried by the machine, so that the blast is directed against the walls of the tube at an acute angle thereto, and with a swirling motion.

Other objects of the invention will become more apparent from the following description, 5 reference being had to the accompanying drawings, in which I have illustrated a preferred form of mechanism for carrying out my improved method. The essential features of the invention will be summarized in the claims. 10

In the drawings, Fig. 1 is an elevation of a tube partially broken away to illustrate my improved tube cleaning machine in operation; Fig. 2 is a view similar to Fig. 1, but illustrating the machine as adapted for use in a tube of a larger diameter 15 than that shown in Fig. 1; Fig. 3 is a vertical section as indicated by the line 3—3 on Fig. 1, illustrating my machine in the elevation; Fig. 4 is an axial section on the forward portion of my improved tube cleaning machine on an enlarged 20 scale, the plane of the section being substantially parallel to the plane of Fig. 1; Fig. 5 is an axial section on the rear portion of my machine, the section being the same as that of Fig. 4, the line 25 a—a of Fig. 5 being the same as line a—a of Fig. 4; Fig. 6 is an axial section, as indicated by the line 6—6 of Fig. 5, the plane of such section being normal to the plane of Figs. 4 and 5; Figs. 7 to 10 inclusive are radial sections as indicated by the correspondingly numbered lines on Fig. 5; 30 Figs. 11, 12 and 13 are radial sections, as indicated by the lines 11—11, 12—12 and 13—13, respectively, of Fig. 4. Fig. 14 is a side elevation partially in section of a modified form of my invention; Fig. 15 is a sectional detail as indicated 35 by the lines 15—15 on Fig. 14.

My improved method comprises directing a blast of abrasive material, such as sand, through a nozzle towards the internal walls of the tube to be cleaned, and advancing the nozzle longitudinally through the tube, while causing the nozzle to direct the blast of abrasive material in a spiral path around the walls of the tube without rotating the nozzle, its supporting mechanism, or the conduits which furnish the nozzle with abrasive 45 material and compressed air or steam which is used to provide the blast, and I prefer to utilize a portion of the compressed air or steam to move the nozzle for obtaining the swirling action of the abrasive material. 50

Referring again to the drawings, and especially to Fig. 1, wherein I have illustrated a preferred form of apparatus for carrying out my improved method, it will be seen that I have provided a cylindrical shaped body 10, of such diameter that 55

- it may readily be introduced into a boiler tube, such as the tube T. Flexible conduits 11 and 12 are connected to the rear end of the body. The conduit 11 supplies the body with abrasive material or grit, such as sand, which is forced into such conduit with air or steam pressure by any suitable apparatus, not illustrated, but which is generally well known and used in the sand blasting art to conduct sand to the blasting jets. The conduit 12 supplies air or steam, under pressure of about one hundred pounds to the square inch, to the body where it is introduced into the grit stream, as will be hereinafter more fully explained.
- 15 At the forward end of the body is a nozzle 14 which is positioned at an acute angle to both the body and the tube. The nozzle is wobbled or moved bodily in a circular path within the tube, without actually rotating the nozzle or the body.
- 20 As neither the nozzle nor the body rotate within the tube, the body may be progressed longitudinally therethrough without danger of twisting the flexible conduits 11 and 12. This feature also permits the body to be progressed by merely
- 25 pushing or shoving the conduits into the boiler tube. The conduits, while flexible, are nevertheless semi-rigid, due to the presence of grit in one and the comparatively great air pressure in the other.
- 30 The body 10 comprises a series of apertured cylindrical members joined together, by suitable bolts 15, to form an integral unit. In general, each body member has four apertures 6, 7, 8 and 9, which coact with similar apertures in other body members to form four longitudinally or axially extending passageways 16, 17, 18 and 19. The passageway 16 is in communication with the conduit 11 which supplies grit to the mechanism. The passageway 17 provides chambers for an air motor and suitable reduction gearing which serve to wobble the nozzle. The passageway 18 is in communication with the air conduit 12, and introduces steam or air under pressure, preferably the latter, to both the motor and the nozzle. The remaining passageway 19 serves as an exhaust passageway for the air motor.
- 35 The left hand body member 26, Figs. 5, 6 and 7, serves as a cap, and is provided with threaded openings 21 and 22, communicating with passageways 16 and 18, respectively. Suitable threaded connector members 11a and 12a are inserted in the openings and have attached thereto, by any suitable clamping means (not shown) the conduits 11 and 12.
- 40 The air motor comprises a pair of rotors 25, secured together as a unit, as will be hereinafter more fully described, and provided with oppositely extending axial stub-shaft portions 26 which are journalled in bearings 27 and 28, carried by the body members 30 and 70, respectively.
- 45 The rotors are somewhat less in diameter than their respective cylindrical chambers 31 of the passageway 17. The axis of each chamber is parallel with but eccentric to the axis of the rotors. The arrangement is such that the upper portion of each rotor engages the upper wall of its respective chamber, as shown in Fig. 9.
- 50 Each rotor 25 is provided with a diametric slot 33, in which a pair of vanes 34 are slidably mounted end to end. Suitable springs 35 are interposed between the vanes of each pair, and retain the outer edges of each vane in engagement with the wall of its respective chamber 31 at all times. The two rotors are connected by a hub portion 36, of smaller diameter than the

rotors, and arranged to be embraced by a body member 50 which forms a valve controlling the intake and exhaust of air to and from the chambers 31.

The body member, or valve plate 50 is best illustrated in Figs. 6 and 8. It is there shown, as provided with apertures 16a, 17a, 18a and 19a which partially form the passageways, heretofore mentioned. The valve plate is provided with a lateral passageway 38, which communicates with an air pressure passageway 18, and both rotor chambers 31. A similar laterally extending passageway 39 in the valve plate 50 connects the discharge passageway 19 with both rotor chambers 31. Air under pressure, therefore, enters the chambers 31 and acting on one of the vanes 34 of each rotor, as indicated in Fig. 9, rotates the rotor in a counter-clockwise direction, until the opposite vane clears the passageway 38, at which time the first vane will have moved into position to uncover the exhaust passageway 39. This is the usual operation of an air motor of this type and hence a more complete description appears unnecessary.

As heretofore mentioned, I have provided two rotors 25. The vanes of one of these rotors are positioned at right angles to the vanes of the other rotor. This prevents the stopping of the rotor unit in a dead center position and insures continuous operation whenever air pressure is applied through the conduit 12.

The speed of the rotors is limited by the back pressure in the passageway 19. As shown in Fig. 6, the body cap member 20 closes one end of the passageway 19, while the body member 80, which closes the other end of such passageway, is provided with restricted openings 41, thereby maintaining a constant back-pressure on the vanes of the rotors.

For convenience in assembling and manufacturing, the two rotors 25 are separately made and are secured together by suitable bolts or rivets 42. The right hand rotor (Fig. 5) is provided with a reduced hub portion 43, which, when assembled, is embraced by the hollow hub portion 44 of the left-hand rotor. By so making the rotors, the slots 33 may readily be cut into the hub end of respective rotors, thereby greatly facilitating the manufacture of the unit.

The speed of the air motor, while somewhat limited by the back pressure in the exhaust passageway, is reduced by the use of compound external-internal speed reduction gearing, which is retained within the passageway 17, and also serves to increase the power available to wobble the nozzle. As shown in Figs. 5 and 10, the forwardly extending shaft portion 26 of the rotor unit has a reduced portion 45, the axis of which is eccentric to the axis of the rotor. Rotatably mounted on this eccentric portion of the rotor shaft is a pinion 47, which constantly meshes with an internal gear 48 and an internal gear 49, having the same pitch diameter but one more tooth than the gear 48.

The internal gear member 48 is secured to the body member 70, and is prevented from rotation relative thereto by a key 51. The other internal gear member 49 is rigidly secured to a shaft 52, journalled in a bearing 53 in the body member 80. Every time the external gear 47 makes one complete revolution relative to the internal gear 48, the internal gear 49 is rotated a distance equivalent to one tooth. Hence, if the gears 48 and 49 are provided with 15 and 16 teeth respec-

tively a sixteen to one reduction is obtained between the shaft 26 and shaft 52.

The speed of the shaft 52 is further reduced by the use of another compound internal-external gear reducing member. As shown, a spur gear 55 is rotatably journalled on an eccentric portion 56 of the shaft 52 and meshes simultaneously with internal gears 57 and 58. The gear 58 is secured against rotation in the body member 80 by a suitable key such as indicated at 59. The gear 57 is drivingly secured to a shaft member 61 mounted in suitable bearings 62 in the body member 90. Hence, if the gears 57 and 58 are provided with 15 and 16 teeth respectively, the result will be a 15 to 1 reduction between the shafts 52 and 61.

The shaft 61 serves to wobble a bearing member 68. As shown in Fig. 4, the right-hand end of the shaft 61 is secured to a curved tube 65, the outer end of which projects forwardly, at an angle to the axis of the shaft, and has secured thereto a jet member 66. The jet is rotatably mounted in suitable bearings 67, carried by the annular bearing member 68. The bearing member abuts, at one end of the tube 65, and at the other end a cap member 69 secured to and forming part of the jet 66, thereby preventing axial movement between the jet and the bearing member.

The bearing member 68 wobbles the nozzle 14, which in turn serves to prevent rotation of the bearing member. As shown in Figs. 4 and 13, the bearing member 68 is connected with a ring 71 by integrally formed connecting posts or bars 72. The nozzle 14 comprises an apertured member 74, mounted in a retaining ring 75, which is secured to the ring 71 by suitable bolts 76. Threadingly secured to the right-hand body member 100 is a collar 101 and similarly secured to the ring 71 is a collar 102. The two collars are connected by a flexible conduit 105, comprising a metallic guard 108 and a flexible rubber or composition tube 107. The metallic guard is preferably a flexible metal tube and is brazed or otherwise secured to the respective collars 101 and 102, thereby preventing rotation of the nozzle, while permitting it to wobble about the axis of the right-hand end of the wobbler tube 65.

Sand is fed to the nozzle 14 through the passageway 16, which communicates with an opening 109 in the body member 100, through which the sand or grit enters the flexible tube 105. The compressed air or steam under pressure entering through the passageway 18, as shown in Fig. 6, is fed into a chamber 110 in the body member 100 and passes through openings 111 in the hollow tube 61, which is in communication with the hollow tube 65 and the jet member 66. The air therefore carries or ejects the sand through the nozzle 74 in the form of a blast.

The various bearings and shafts are lubricated with oil stored in a chamber 120 within the body member 20. As shown, this body member is provided with suitable opening adapted to be closed by a plug 121 so that oil may be supplied to the chamber 120 from time to time. A felt or fibrous washer member 122 retains the bulk of the oil within the chamber 120, but permits the filtering or seeping of the oil into the passageway 16, where it lubricates the various bearings and the rotor vanes. The oil is conducted from one of the vane slots through a tubular passageway 124 in the sub-shaft 26 of the rotor into the chamber 125, which contains the reduction gearing 45, 48 and 49, from whence an axial opening 126 in the shaft member 52 permits the oil to flow into

the chamber 121, which encloses the reduction gearing 55, 57 and 58. Suitable oil passageways 128 in the shaft member 61 permit the oil to lubricate the bearing member 62. A small passageway 129 between the air pressure conduit or 5 passageway 18 and the oil chamber 128 equalizes the pressure on the oil.

The bearings 68 and 67 are lubricated by moisture and oil which is conveyed to the jet 66, by the compressed air stream. As shown, a suitable 10 opening 130, communicating with the blast passageway 131 of the jet, and with a hollow groove or recess 133 in the bearing member permits moisture to enter and lubricate such bearing.

The body, as shown in Fig. 1, is slightly smaller 15 than the internal diameter of the tube T. To adapt the body to larger diameter tubes, such as is illustrated at T in Fig. 2, I prefer to provide a carriage, such as is shown in Figs. 2 and 3, and which maintains the body substantially in the 20 center of the tube and thereby enables the grit to act against the inner wall of the tube with substantially the same force in any direction.

The carriage comprises a pair of bands 143 arranged to be clamped in position on the body. 25 Pivoted to each band 143 are a series of equi-spaced links 141. Each link is pivoted at one end to its respective ring and at the other end carries a roller 142 adapted to engage the inner walls of the tube. The corresponding links 141 of each 30 ring 140 are pivoted together intermediate their ends, as at 144. Hence, by adjustably positioning the clamping rings axially of the body, the carriage may readily be adjusted for different 35 diameters of tubes.

As heretofore described, my improved tube cleaner utilizes a blast of abrasive material, such as sand or mineral grit for cleaning tubes. Materials such as these are apt to cause premature wear on the walls of the grit passageway 16. 40 In the form of the invention illustrated, in Figs. 1 to 13 inclusive, the grit passageway 16 is formed integral with the body members 30, 40, 50, 60, 70, 80 and 90. Hence, in event of excessive wear, due to the use of certain grits, such members 45 might require replacement. I therefore may prefer to provide a grit passageway independent of such body members. Such an independent passageway eliminates the entrance of grit in the air motor and gear reduction mechanism in event 50 of complete erosion of the walls of the passageway.

In Figs. 14 and 15 I illustrate a modified form of body provided with a series of body members similar to the correspondingly numbered body members heretofore described. In this instance, however, the intermediate body members each have recesses 170 formed in their outer walls. Such recesses are aligned to form a channel 171 arranged to receive a removable tubular member 172 having walls formed complementary with the walls of the channel 171 and an outer wall forming substantially a continuation of the cylindrical contour of the body. The ends of the tube 172 about the openings 6 in the body members 20 and 100, suitable gaskets 175 being interposed therebetween to insure a tight joint consequent upon the clamping of the tube in position by the tightening of the body bolts 15. This, therefore, eliminates replacement requirements for the intermediate body parts and their complicated mechanisms.

From the foregoing description it will be seen that I have provided a simple yet effective method of economically cleaning the inner walls of 75

boiler tubes, without danger of injuring them, by applying a sand blast to the walls through a mechanism which may be inserted and fed through the tube to be cleaned, and I have provided a mechanism for causing the sand to be applied with a spiraling motion, which mechanism may be inserted in tubes of comparatively small diameters, and which mechanism contains a power unit and reduction gearing to wobble a sand blast nozzle, while preventing actual rotation of the machine itself, the nozzle or connecting conduits.

I claim:

1. A mechanism for cleaning tubes, comprising a body adapted to be wholly inserted in the tube to be cleaned, conduit means communicating with the body, a nozzle carried by the body, means for ejecting a blast of abrasive material through the nozzle toward the wall of the tube to be cleaned, and power operated means carried by said body and reacting thereon to move the nozzle relative to the body and transversely of the tube.

2. A mechanism for cleaning tubes, comprising a body adapted to be wholly inserted in the tube to be cleaned, a conduit communicating with the body, a nozzle carried by the body, means carried by the body and communicating with said conduit to eject an abrasive material from said body towards the wall of the tube, and a power-operated mechanism carried by said body to move the nozzle relative to the body while the body is being progressed through the tube.

3. A mechanism for cleaning tubes comprising a body adapted to be inserted wholly in the tube to be cleaned, a conduit for abrasive material connecting the body, a nozzle movably carried by the body, means to cause an abrasive material to be ejected from the nozzle toward the wall of said tube, and means operated by said last-named means to move said nozzle relative to the body.

4. A mechanism for cleaning tubes comprising a body adapted to be inserted wholly in the tube to be cleaned, a conduit for abrasive material connecting with the body, a pressure conduit communicating with the body, a nozzle carried by the body and communicating with both of said conduits to cause an abrasive material to be ejected from the nozzle, and a motor carried by said body to continuously move the nozzle.

5. A mechanism for cleaning tubes comprising a body adapted to be inserted in the tube to be cleaned, a conduit for abrasive material connecting the body, a pressure conduit communicating with the body, a nozzle carried by the body, a jet mechanism carried by the body and communicating with both of said conduits to cause an abrasive material to be ejected from the nozzle, an air motor operated from air pressure and carried within said body to move the nozzle, and means to maintain the nozzle at an acute angle to the wall of the tube being cleaned.

6. A mechanism for cleaning tubes, comprising a body adapted to be inserted in the tube to be cleaned, a conduit communicating with the body, a nozzle carried by the body whereby material may be ejected from the body toward the wall of the tube, reduction gearing mounted in said body, and power operated mechanism for applying power to said reduction gearing to move the nozzle continuously.

7. A mechanism for cleaning tubes, comprising a body adapted to be inserted in the tube

to be cleaned, a conduit communicating with the body, a nozzle carried by the body, whereby material feed to the body through said conduit may be ejected from the body toward the wall of the tube, and a power-operated mechanism mounted in said body to wobble the nozzle relative to the tube to be cleaned.

8. A mechanism for cleaning tubes, comprising a body member adapted to be inserted in the tube to be cleaned, a flexible conduit communicating with the body and adapted to convey an abrasive material thereto, a second flexible conduit communicating with the body and adapted to convey air under pressure thereto, a nozzle carried by said body through which abrasive material is ejected from the body in the form of a blast by air pressure, an air motor, and means operated by a portion of the air pressure to cause a wobbling movement to be imparted to said nozzle.

9. A mechanism for cleaning tubes, comprising a body member adapted to be inserted in the tube to be cleaned, a conduit communicating with the body and adapted to convey an abrasive material thereto, a second conduit communicating with the body and adapted to convey air under pressure thereto, a nozzle, means whereby the abrasive material is ejected from the nozzle by air under pressure, an air motor, means operated thereby to impart a wobbling movement to said nozzle, said last-named means including a speed reducing gearing and a wobbler operatively connected to such gearing and to said nozzle.

10. A mechanism for cleaning boiler tubes and the like, comprising a series of apertured members secured together to form a body having a plurality of axial passageways, a flexible conduit adapted to convey an abrasive material to one of said passageways, a flexible conduit adapted to convey a blast to another of said passageways, a motor mounted in another of said passageways, a communication between said motor and said blast, whereby said blast operates said motor, reduction gearing operatively connected with said motor and carried in said last-named passageway, a hollow shaft operatively connected to said gearing and communicating with said blast passageway, a jet carried by said shaft, a nozzle spaced from said jet and in communication with the abrasive and blast passageways, bearing interposed between said shaft and said nozzle, said bearing coacting with a portion of said shaft projecting at an angle to the main portion thereof, a flexible connection between the nozzle and the body adapted to prevent relative rotation therebetween, whereby said nozzle is caused to wobble when the blast stream is fed to the body without rotating the body or the nozzle or the conduits relative to the tube to be cleaned.

11. A mechanism for cleaning tubes, comprising a body member, a nozzle movably carried by said body and through which abrasive material may be ejected toward the walls of the tube, and a flexible metal conduit connecting the nozzle with said body and forming a passageway for abrasive material, said tube being lined with a flexible composition material.

12. A mechanism for cleaning tubes comprising an elongated body, an air motor and reduction gearing mounted in substantial axial alignment with each other in said body, a lubricant reservoir, a lubricant passageway through said motor and said gearing, a fibrous washer dis-

posed between the lubricant passageway and said lubricant chamber, a pressure conduit in said body and a passageway communicating with said chamber and the pressure conduit to force a lubricant through said lubricant passageway to lubricate the motor and the gearing.

13. A mechanism for cleaning tubes comprising a substantially cylindrical body member having a longitudinal recess in its outer wall and adapted to be inserted in a tube to be cleaned, a conduit for an abrasive material connected to one end of said body, a nozzle at the other end of the body and through which abrasive material is directed toward the walls of the tube to be cleaned, nozzle operating mechanism within said body, means communicating with said nozzle and said conduit, said last-named means comprising a member removably inserted in the body recess.

20 14. An apparatus for cleaning tubes comprising a nozzle adapted to be inserted into the tube to direct an abrasive blast against its interior surface, a support for the nozzle and means reacting on the support to wobble the nozzle without rotating it.

15. An apparatus for cleaning tubes comprising a nozzle adapted to be introduced into such tube, means for ejecting a blast of abrasive material from the nozzle, means adapted to be advanced through the tube, arranged for supporting the nozzle with its operating axis directed at an acute angle to the tube surface, and means reacting on the support and operatively connected with the nozzle to wobble it about.

35 16. An apparatus for cleaning tubes comprising a nozzle adapted to be introduced into such tube, a conduit adapted to feed abrasive material through the nozzle under pressure, means to guide the nozzle for advancement along the

tube, and means to impart a wobbling motion to the nozzle without rotating the conduit.

17. A tube cleaning tool having a nozzle and supporting body therefor, and means reacting on the body to cause the nozzle to wobble in a fixed conical path.

18. A mechanism for cleaning tubes, comprising a body adapted to be wholly inserted in the tube to be cleaned, conduits communicating with the body, a nozzle carried by the body, means to progressively move the nozzle so that its axis follows a substantially conical path relative to the body, and means for ejecting a blast of abrasive material through the nozzle toward the wall of the tube to be cleaned.

19. A mechanism for cleaning tubes, comprising a body adapted to be wholly inserted in the tube to be cleaned, a nozzle carried by the body, means to eject a blast of abrasive material from said nozzle towards the wall of the tube to be cleaned, means to maintain the nozzle at an acute angle relative to the axis of the tube, and power mechanism carried by said body and means connecting said mechanism to the nozzle to move the nozzle circumferentially of the tube during the ejection of said blast of abrasive material.

20. A mechanism for cleaning tubes of varying diameters comprising a body adapted to be inserted wholly in the tube to be cleaned, means for supplying air under pressure and abrasive material to the body, a nozzle carried by the body whereby the abrasive material may be ejected from the nozzle toward the wall of said tube, and adjustable centering means arranged to continuously engage the tube at three spaced points circumferentially of the tube and on the inside thereof to maintain the body axially located relative to the wall of the tube.

ALBERT CARTER,
